UNITED STATES PATENT OFFICE.

LOUIS T. MICKE, OF OWENSVILLE, MISSOURI.

CARTRIDGE-MAGAZINE.

1,099,992.

Specification of Letters Patent. Patented June 16, 1914.

Application filed April 19, 1913. Serial No. 762,324.

To all whom it may concern:

Be it known that I, LOUIS T. MICKE, a citizen of the United States, residing at Owensville, in the county of Gasconade and State of Missouri, have invented certain new and useful Improvements in Cartridge-Magazines, of which the following is a specification.

This invention relates to fire-arms and more particularly to improvements in the magazines or storing chambers for the cartridges or shells used with rifles or similar guns.

An object of this invention is to provide a cartridge or shell magazine, principally to be used for rifles, which is formed within the stock of the gun and one which will be positive and unfailing in action; will aid in balancing the fire-arm as well as affording a convenient and practical manner for carrying the ammunition from place to place, and also one from which the ammunition may be easily and quickly extracted as desired.

With the foregoing and other objects in view, this invention consists in such novel features of construction, combination and arrangement of parts as will be hereinafter more fully described, illustrated in the accompanying drawings, and claimed.

In describing the invention in detail, reference will be had to the accompanying drawings wherein like characters of reference designate like or corresponding parts throughout the several views, and in which—

Figure 1 is a fragmentary sectional view through the stock of the fire-arm; Fig. 2 is an end view, showing the recoil plate removed and the mechanism for dispensing of the cartridges in such a position as to prevent the cartridges from being extracted from the magazine; and Fig. 3 is a view similar to Fig. 2 only showing the mechanism in a position to allow of the extracting of the cartridges.

In referring to the drawings by numeral, 1 designates the stock of a fire-arm of the type commonly known as a rifle which has the recoil plate 2 mounted upon its outer or large end 3 by means of the screws 4. The recoil plate 2 has an aperture 5 extending therethrough which communicates with a cut-out portion 6 formed in the end of the stock 1. An elongated chamber 7 extends inwardly into the stock 1 of the gun, and

forms a chamber for the reception of shells 8, such as are used in the fire-arm.

Mounted in the lower end of the elongated chamber 7 is a member 9 one portion of which projects upwardly into the chamber and forms a guide-way for the shells 8 to facilitate the insertion of the same into the chamber or the extraction of them from the member 9 which has the enlarged plate or projection 10 formed upon its lower end which enters the enlarged cut-out portion 6 and engages the upper end of the member 11. The member 11 has an opening 12 centrally located therein which is adapted at times to coincide with the opening in the member 9 and the handle portion 13 which extends outwardly past one side of the gun stock 1 so as to be accessible by the finger of the person using the fire-arm. The member 11 has a portion 14 formed integral therewith and extending inwardly into the enlarged portion of the cut-out portion 6 and pivotally mounted upon the pin 15 which is mounted in the stock 1.

A cut-out portion 16 is formed in the stock and communicates with the cut-out portion 6 and has a twisted portion 18 of the spring 17 mounted therein. The end 19 of the spring 17 is mounted in one side of the stock 1 as is shown at 20 while the other end 21 engages one side of the member 11 and tends to hold it in the position as illustrated in Figs. 1 and 2 of the drawings or so as to prevent the cartridges from falling out of the magazine through the opening 5 in the recoil plate 2.

When it is desired to insert the cartridges 8 into the elongated chamber 7 the member 11 is moved by means of the handle portion 13 until the opening 12 therein coincides with the opening 5 in the recoil plate. A cartridge is then inserted within the opening 12 of the member 11 and the pressure is released from the handle. The spring 17 will then force the member 11 back into a position as is shown in Figs. 1 and 2 or in a position so that the opening 12 will coincide with the opening in the member 9 and with the elongated chamber 7. The shells 8 will then fall, by means of gravitation, out of the opening 12 and into the chamber 7, provided the gun is inverted so that the mouth of the barrel of the same is pointing downward. This operation is repeated until the elongated chamber 7 is completely filled with cartridges or until the desired num-

ber of cartridges has been inserted within the chamber.

When it is desired to remove the cartridges from the chamber 7, the gun is held 5 in a position so that the weight of the shells will force them, one at a time, into the opening 12. The member 11 is then actuated by means of the handle 13 and the cartridge contained within the opening 12 10 will fall through the opening 5 into the hand of the person using or operating the means and when the handle portion 13 is relieved of pressure, the spring will force the member 11 back so as to receive a second 15 cartridge from the chamber.

In practical fields, certain minor features of construction, combination and arrangement of parts may necessitate alterations to which the patentee is entitled, provided 20 such alterations are comprehended within the scope of what is claimed.

What is claimed is:—

1. The combination with a gun stock having an elongated chamber extending inwardly therein, an enlarged cut out portion 25 formed within the other end of the stock and communicating with one end of said chamber and a plate secured to the outer end of said stock, said plate provided with an opening out of line with said chamber, of means 30 movably mounted within said cut out portion and alternately registering with the chamber and the opening in the butt plate for effecting the discharge of one cartridge at a time and simultaneously preventing the discharge of the following cartridge during the egress of the discharging cartridge.

2. The combination of a gun stock having 40 an elongated chamber formed therein, a cut out portion communicating with said elongated chamber and a plate secured to the outer end of said stock, said plate provided with an opening out of line with said chamber, of a tubular member pivotally mounted 45 within said cut out portion and normally

registering with said chamber, and means for swinging said member laterally of said elongated chamber into coincidence with the opening in the butt plate whereby a cartridge contained in said chamber may be extracted therefrom.

3. The combination of a gun stock having an elongated chamber formed therein, a cut out portion communicating with said elongated chamber and a plate secured to the outer end of said stock, said plate provided with an opening out of line with said chamber, of a tubular member pivotally mounted within said cut out portion, means for holding said tubular member in alinement with said chamber, and means for swinging said tubular member laterally of said elongated chamber whereby to allow said tubular member to aline with the opening in 65 said plate.

4. The combination of a gun stock having an elongated chamber formed therein, a cut out portion communicating with said chamber and a plate secured to the outer end of 70 said stock, said plate provided with an opening out of line with said chamber, of a tubular member pivotally mounted within said cut out portion and normally registering with said chamber, resilient means disposed within said cut out portion and bearing against one end of said cut out portion and said tubular member for holding said member in alinement with said chamber, and a handle formed upon said tubular 75 member for swinging the member laterally of said elongated chamber into coincidence with the opening of the butt plate whereby a cartridge contained in said chamber may be extracted therefrom.

In testimony whereof I affix my signature in presence of two witnesses.

LOUIS T. MICKE.
